WALL STRUCTURE WITH INTERLOCKED BLOCKS
Morton M. Rosenfeld, 271 Madison Ave.,
New York, N.Y.
Filed Oct. 6, 1961, Ser. No. 143,363
2 Claims. (Cl. 50—78)

This invention relates to a wall structure, and more particularly, to a wall structure having blocks interlocked with each other by means of rod-like members.

Heretofore, numerous wall structures have been suggested wherein the blocks are designed so as to have interlocking members. Such interlocking members not only increase the strength of the wall but provide a means for orientating one block with respect to another. Such wall structures do not provide for interlocking and orientating of blocks juxtaposed to one another in a single course of blocks in the wall.

There is a need for a wall structure which is internally reinforced so that it may resist large forces to which it may be subjected. The wall structure of the present invention is readily adaptable for use in bombshelters air raid shelters, safety shelters in areas wherein bombs and other explosives are being tested, building foundations, etc. In accordance with the present invention, blocks one above the other in a wall are interconnected and orientated with respect to each other by means of rod-like members. Also, the blocks in a single course are orientated with respect to each other and interconnected by means of rod-like members extending across the juxtaposed ends of adjacent blocks. The last mentioned rod-like members are interconnected with rod-like members which interconnect blocks one above the other in separate courses.

In one embodiment of the present invention, the rod-like members transversing the ends of juxtaposed blocks in a single course are separate discrete members. Another embodiment of the present invention shows the rod-like members traversing the ends of juxtaposed blocks in a single course are integral with the rod-like members extending between blocks in courses on above the other. In the last mentioned embodiment of the present invention, the rod-like members which traverse the blocks in a single course are preferably of a length not less than the length of a single block.

It is an object of the present invention to provide a novel wall structure wherein courses of blocks are interlocked with each other by a layer of mortar and reinforcement rod-like members.

It is another object of the present invention to provide a wall structure wherein successive courses of blocks are interlocked by means of rod-like members, and juxtaposed blocks in a single course are interlocked with each other.

It is another object of the present invention to provide a wall structure wherein successive courses of blocks are interlocked with each other by rod-like members, and with juxtaposed blocks being interlocked by means of rod-like members which interconnect with the first mentioned rod-like members.

It is still another object of the present invention to provide a wall structure wherein successive courses of blocks are interlocked with each other and juxtaposed blocks in a single course are interlocked with each other by means of rod-like members which are in the form of a plurality of T-shaped members interconnected with one another.

It is still another object of the present invention to provide a wall structure having means for interconnecting and orientating blocks in a single course as well as a

2

plurality of successive courses in a manner so that the wall may be a dry wall or a wet wall.

Other objects will appear hereinafter.

For the purpose of illustrating the invention there is shown in the drawings forms which are presently preferred; it being understood, however, that this invention is not limited to the precise arrangements and instrumentalities shown.

FIGURE 1 is a perspective view of a partially constructed wall in accordance with the present invention.

FIGURE 2 is a longitudinal sectional view of the wall illustrated in FIGURE 1.

FIGURE 3 is a transverse sectional view taken along the lines 3—3 in FIGURE 2.

FIGURE 4 is an exploded view of the interconnecting and orientating members in the wall illustrated in FIGURES 1—3.

FIGURE 5 is an end view of the rod-like member for interconnecting successive courses of blocks.

FIGURE 6 is a longitudinal sectional view, similar to FIGURE 2, of another embodiment of the present invention.

FIGURE 7 is a perspective view of the rod-like member shown in FIGURE 6.

FIGURE 8 is a perspective view of one end of a connecting member of another embodiment of the present invention.

Referring to the drawing in detail, wherein like numerals indicate like elements, there is shown in FIGURE 1 a wall structure designated generally as 10.

The wall structure 10 is illustrated as being formed on a supporting surface or floor 12. The wall structure 10 is separated from the floor 12 by means of a first layer of mortar 14. A first course 16 of rectangular shaped blocks 18 is positioned over the first layer of mortar 14.

The blocks 18 may be of conventional dimensions and may be made from cinder block, cement, mixtures of concrete and other materials, etc. The blocks 18 are provided with a longitudinally extending groove 20 on a top surface substantially equidistant from the side faces. The groove 20 has a length corresponding to the length of the blocks 18. Also, each block 18 has a longitudinally extending groove 22 on a bottom surface. The grooves 20 and 22 are disposed so that they are one above the other. The grooves 20 and 22 are of the same dimensions and are semi-circular in transverse cross section. The groove 22 extends for the full length of the blocks 18 and is spaced substantially equidistant from side faces of the blocks 18.

Each of the blocks 18 is provided with a hole 24 and a hole 26 extending between the top and bottom faces. The holes 24 and 26 are positioned so as to be located at a point spaced from the adjacent end face of the block by a distance corresponding to approximately one-fourth the length of the blocks. The holes 24 and 26 are also positioned so as to be substantially equidistant from the side faces of the blocks 18 thereby emerging through the top and bottom faces of the blocks in the grooves 20 and 22.

The wall 10 may be interlocked with the floor 12 in the following manner. The floor 12 may be provided with a plurality of blind holes 28 positioned so as to correspond with the spacing between the holes 24 and 26. Thus, the holes 28 will be in line with one another and spaced apart by a distance corresponding to approximately one-half the length of the blocks 18. The first course 16 of the blocks 18 will be interconnected with the floor 12 by means of rod-like members 30 which have one end in the holes 28 and their opposite end extending into the blocks 18 for a distance corresponding to approximately one-half the height of the blocks 18. The holes 28 are substantially the same diameter as the holes

70

24 and 26. The annular area between the inner peripheral surface of the holes 24, 26 and 28 and the outer periphery of the rod-like members 30 may be filled with mortar.

The first course 16 of blocks 18 will be interconnected with the floor 12 by the layer of mortar 14. Also, the blocks 18 in the first course 16 will be interconnected with each other by a layer of mortar between juxtaposed end faces of the blocks. In order to interconnect successive courses of blocks 18, rod-like members 32 are provided. As shown more clearly in FIGURE 4, the rod-like members 32 are provided with a bulbous or spherical portion 34 at a point substantially equidistant from each end. The spherical portion 34 is provided with a notch 36 extending in a direction parallel to the longitudinal axis of the rod-like member 32 and a stripe 38 therearound. The width of the stripe 38 will act as a guide to designate the thickness of the layer of mortar between successive courses. A connector member 40 extends between the rod-like members 32 which are disposed on opposite sides of juxtaposed end faces of blocks 18 in a single course. The connector member 40 has its ends received in the slot 36 in each spherical portion 34.

The spherical portion 34 is provided with dimensions slightly smaller than the circle formed by the juxtaposed semicircular grooves 20 and 22. The connector member 40 will likewise have dimensions so that it may be disposed within the circle formed by said grooves as shown more clearly in FIGURE 3.

The remaining elements of the wall structure 10 are more readily explained in conjunction with the description of the manner in which the wall 10 is constructed as set forth hereinafter.

In order to construct the wall structure 10, the floor 12 will be provided with a line of holes 28 which are equidistant from each other. The provision of the holes 28 may be eliminated if it is not deemed necessary to mechanically lock the wall structure 10 to the floor 12. Assuming that the provision of the holes 28 is desirable, the next step is to insert the rod-like members 30 into the holes 28. Thereafter, the first layer of mortar 14 is provided on the floor 12.

The next step in the construction of the wall structure 10 is the laying of the first course 16 of the blocks 18. The blocks 18 will be positioned so that the rod-like members 30 enter the various holes 24 and 26. After the first course 16 of the blocks 18 has been properly laid, a rod-like member 32 is inserted in each of the holes 24 and 26. Due to irregularities of the blocks, the spacing between the ends of the rod-like members 32 and the rod-like members 30 will vary.

The rod-like members will be disposed in a manner so that the slots 36 in the spherical portion 34 of each member 32 will be facing the adjacent end face of its respective block. Then a connector member 40 will be positioned in the groove 20 across the juxtaposed end faces of adjacent end blocks in the course 16. The ends of the connector member 40 will be disposed within the slots 36. Thereafter, the second layer of mortar 42 may be provided over the first course 16 of blocks 18. The thickness of the layer of mortar 42 may be gauged by the width of the stripe 38 on each of the spherical portions 34.

Then a second course 44 of blocks 18 may be provided on the first course of blocks and the layer of mortar 42. As each block is put in position while forming the course 44, the blocks are located in a manner so that the upper end of the rod-like members 32 enters the holes 24 and 26. Thereafter, the layer of mortar 46 and course 48 of blocks 18 are provided in the manner described above until the wall structure 10 has the desired height.

The rod-like members 32 interconnect the various courses which are disposed one above the other thereby orientating the various blocks in the courses as well as

reinforcing the wall structure 10. The rod-like members facilitate sighting of one block with respect to adjacent blocks to assure proper alignment. The ends of the members 32 will be located at a point substantially equidistant from top and bottom faces on superimposed blocks of two different courses.

The connector member 40 interconnects adjacent rod-like members 32 across the juxtaposed end faces of blocks in the same course. In this manner, a rigid lattice work is provided by the members 32 and 40 which strengthens the wall structure and facilitates the rapid construction of a wall. Since the stripe 38 designates the thickness of the layer of mortar between adjacent courses, and since the blocks of the various courses will be interconnected and orientated with respect to each other, a wall structure may be constructed in a more rapid manner by a man who is unskilled in the art of masonry.

If desired, the grooves 20 and 22 on the blocks 18 and the spherical portion 34 on the members 32 may be eliminated. In this case, the connecting member would be a flat strip 40', see FIGURE 8, having a hole adjacent each end through which the member 32 would extend. The thickness of strip 40' may be equal to or less than the thickness of the layer of mortar, if any, between the blocks. Preferably, the strips 40' would be located in the same manner as members 40 and would have a width less than the width of the blocks. It will be appreciated that the members 40 and strips 40' may be interconnected with any of the members 32 if desired.

In FIGURE 6, there is shown another embodiment of the present invention designated generally as 10'. The wall structure 10' is identical with the wall structure 10 except as will be made clear hereinafter. In the wall structure 10', the blocks 18' are interconnected and orientated with the blocks thereabove and adjacent thereto in the same course by means of a connecting member 50. The connecting member 50 has a length which is not less than the length of one of the blocks 18'. As illustrated, the connecting member 50 has a length corresponding to the length of two blocks 18'. The member 50 is provided with rod-like members or pins 52 extending therefrom in opposite directions at spaced points therealong. The pins 52 are integral with the member 50.

The distance between adjacent pins 52 corresponds with the distance between the holes 24' and 26' in the blocks 18'. As illustrated, the connecting member 50 is provided with eight (8) pins 52. Thus, the connecting member 50 interconnects five (5) of the blocks 18' in the first and second courses. The length of the connecting member 50 may be increased if desired so as to interconnect a larger number of blocks. As illustrated in FIGURE 6, the connecting member 50 has a thickness corresponding to the thickness of the mortar between the first and second courses. Thus, the blocks 18' need not be provided with grooves on their upper and lower surfaces. However, such grooves may be provided if it is desired to use a rod-like member having a thickness greater than the thickness of the layer of mortar between the first and second courses. Another connecting member 54, identical with member 50, will be utilized to interconnect and orientate the next five (5) blocks of the first and second courses. Thus, the wall 10' will utilize a plurality of connecting members, such as member 50, to interconnect and orientate adjacent successive courses. The wall 10' may be constructed more rapidly than the wall 10 because of the integral nature of the member 50 and pins 52.

In constructing the wall 10', it is preferable to utilize two sizes of the members 50. In this manner, the juxtaposed ends of the members 50 will not be one above the other. This may be readily accomplished by having the length of member 54 correspond to the length of three (3) of the blocks 18'.

In each of the embodiments of the present invention, a reinforced wall structure is provided with blocks being

interconnected and orientated with respect to an adjacent block in the same course as well as blocks in the course above and therebelow. In each of the embodiments of the present invention, the rod-like members may be made from wood, plastic, etc. but are preferably made from metal.

The present invention may be embodied in other specific forms without departing from the spirit or essential attributes thereof and, accordingly, reference should be made to the appended claims, rather than to the foregoing specification as indicating the scope of the invention.

I claim:

1. A wall structure comprising a wall formed from a plurality of blocks, a groove extending along the top and bottom face of each block, a pair of spaced holes in each block within the plane defined by said grooves, rod-like members within aligned holes in blocks of adjacent successive courses, said members having ends terminating at a point within said blocks, spherical spacer means intermediate the ends of said members for seating in contacting engagement with the sides of a channel formed by juxtaposition of a groove on a top surface of one block and a groove on the bottom surfaces of the blocks thereabove, a notch formed in each said spacer means, said notch extending in a direction parallel to the longitudinal axis of the rod-like members, and connecting members extending between and interconnected with adjacent ones of said rod-like members, the ends of said connecting members being received in said notches formed

in said spacer means, said connecting members also being disposed within said channel.

2. A wall structure in accordance with claim 1 wherein a layer of mortar is provided between adjacent successive courses of blocks, and indicia means on said spacer means for designating the desired thickness of the layer of mortar between adjacent successive courses.
